UNITED STATES PATENT OFFICE.

RICHARD J. KELLY, OF SYRACUSE, NEW YORK.

WICK-RAISING MECHANISM FOR LANTERNS.

1,241,125.

Specification of Letters Patent. Patented Sept. 25, 1917.

Substitute for application Serial No. 38,398, filed July 7, 1915. This application filed May 15, 1917. Serial No. 168,760.

To all whom it may concern:

Be it known that I, RICHARD J. KELLY, a citizen of the United States, residing at Syracuse, in the county of Onondaga and 5 State of New York, have invented certain new and useful Improvements in Wick-Raising Mechanism for Lanterns, of which the following is a specification.

This invention relates to improvements in 10 lanterns, and has for its object to provide novel, simple and effective means for raising and lowering the wicks without requiring the lifting of the globe or the removal of the oil-pot from the frame. A further object is 15 to provide an operating-gear which is carried by the guard-ring of the lantern frame, and which co-acts with a circular-rack which is pivotally mounted on the oil-pot, for raising and lowering the wick. And a further 20 object is to generally improve, simplify and cheapen the construction of lanterns of the class.

The invention relates particularly to an improvement in the class of wick-raising and 25 lowering devices shown and described in my United States Patent No. 996488, bearing date June 27, 1911.

The various features and parts of the invention will be understood from the detailed 30 description which follows, and by reference to the accompanying drawing, in which—

Figure 1 is a horizontal section taken on line 1—1 of Fig. 2; showing the application of my improvement to a well-known type of 35 lantern.

Fig. 2 is a central vertical section, taken substantially on line 2—2 of Fig. 1; showing the construction, arrangement, and operation of the wick-raising mechanism.

Fig. 3 is an enlarged elevational view of 40 the bell-gear or rack and the pinion which drive and are driven thereby.

In my former patent referred to, I showed the usual wick-raising spindle, on the outer 45 end of which was mounted a pinion which engaged and was driven by a circular rack, the latter being loosely journaled for rotation on the neck of the burner. I next showed a rack-rotating member or shaft, which passed 50 vertically upwardly through the oil-pot, on the upper end of which was mounted a second pinion for rotating said circular rack,

the lower end of the said shaft projecting below the oil-pot and having a thumb-piece 55 for manipulating the said shaft. This construction and arrangement of the wick raising mechanism entailed considerable extra work and expense, which included the piercing of the oil-pot and the insertion of a tube 60 therein for containing and supporting the 65 said upright shaft, besides it required the lantern to be lifted up for gaining access to the thumb-piece. Owing to the fact that the said thumb-piece was positioned at the bottom of the oil-pot it was in danger of being injured, broken, or interfered with in 70 case the lantern was dropped, or whenever the bottom thereof came in contact with some hard substance. It was further necessary, under the former construction and arrangement, to provide means for disconnecting the pinion carried by said shaft from the internal gear, so as to prevent the wick from being accidentally raised or lowered. The 75 object of the present invention is to eliminate the upright shaft and related parts of the former device and to provide a novel, simple and convenient rack-operating means, which is journaled in the guard-ring 80 of the lantern frame, and which is so positioned that the simple insertion of the oil-pot into the frame, operatively connects the said means with the rotatable wick-raising rack, to the end that the said means may be 85 manipulated conveniently from one side of the guard-ring, without requiring any change in the position of the lantern, and the said means is also adequately protected 90 from injury as well as accidental operation at all times. The following is a detailed 95 description of my improvement:

In the drawing, the lantern frame consists of a guard-ring 2, which is cylindrical, and to the bottom of which is secured a flaring base 3. 4 represents the wire guards, 95 and 5 the globe. All of which may follow the usual construction for an open bottom lantern of the class. The base 3 has a relatively large circular opening which is surrounded by an inwardly facing flange 7. 8 represents the oil-pot which is inserted upwardly through the opening in the base 3, and the said pot has an annular flange 9 which engages the underside of the flange 7 100

for substantially sealing the bottom of the lantern, as well as for limiting the insertion of the pot, and a pair of springs 10 carried by the oil-pot engage the opposite sides of 5 the flange 7 for holding the pot in place. The top of the oil-pot has a threaded opening 11, which receives the threaded lower end 12 of the burner, and when the burner is screwed into the pot there is a slight space 10 left between the top of the pot and a shoulder 13 of the burner. The burner is cylindrical and hollow and is pierced axially by the usual flat wick-tube 14, in which the wick 15 is disposed. The upper end of the wick-tube 15 projects slightly above the top of the burner, while its lower end extends downwardly into the pot 8. 16 represents the wick-raising spindle, or shaft, which is journaled in the neck of the burner at right 20 angles to the wick-tube, the said spindle being fitted with the usual star pinions 17, which directly engage the wick. The outer end of the spindle 16 is fitted with a pinion 18, which meshes with a circular rack 19, 25 which is cut in the top of a bell-shaped part 20, the top of the said bell being perforated centrally and pierced by the threaded end of the burner, upon which it is rotated, as best seen in Fig. 2. The depending cylindrical portion of the bell 20 is slightly 30 larger in diameter than the oil-pot and fits loosely over, or telescopes, the top of the said pot, and its lower margin is bent outwardly to provide an annular flange 21 facing the inner sides of the guard-ring. The flange 21 comprises a second circular rack 22, which is engaged and driven by a second pinion 23. The pinion 23 is mounted rigidly 35 on a radial shaft 24 which is journaled in a tube 25, the latter piercing the guard-ring 2, and the outer end of said shaft is fitted with a thumb-wheel 26, by which the pinion 23 is rotated. 27 represents a sleeve which telescopes the inner end of the tube 25 and 40 serves to space the pinion 23 from the guard-ring 2, and also to hold said pinion in the proper position relatively to the rack 22. The shaft 24 is held from longitudinal movement in the opposite direction by a boss or 45 ferrule 28 which is interposed between, and spaces the thumb-wheel 26, from, the guard-ring, and the said boss is rigidly secured to the said ring.

The operation of my improved wick raising and lowering mechanism is extremely simple: The turning of the thumb-wheel 26 to the right and left, respectively raises and lowers the wick 15. The said operations are accomplished in the following manner: 55 When the thumb-wheel 26 and the pinion 23 are turned to the right, the bell-piece 20 is rotated to the left, and the said bell in turn, through the circular rack 19 rotates the pinion 18 to the right for raising the

wick 15. The rotation of the thumb-wheel 65 in the opposite direction will then lower the wick.

By this construction and arrangement of the bell 20, the said part may be readily and cheaply stamped and formed up out of sheet 70 metal, and the top, and flange 21, may then be acted upon by suitable dies for forming the racks 19 and 22. The disposing of the rack 22, as shown and described, permits the oil-pot to be inserted upwardly into the 75 guard ring, against the tension of the springs 10, until the flanges 7 and 9 meet, as described, whereupon the said springs grip the flange 7 for holding the pot in place. When the oil-pot is thus sprung or snapped 80 into place, the larger circular rack 22 is brought into engagement with the underside of the pinion 23, and the said pinion may then be rotated by the manipulation of the thumb-wheel 26 for adjusting the wick. 85 The pinion 23 is constantly in engagement with the rack 22 as long as the pot is held in place, and as the thumb-wheel 26 is permanently attached to the guard-ring, and is disposed between two of the guard wires 90 4, there is no danger of the said wheel coming into contact with any foreign substance, which would disturb the adjustment of the wick.

It is obvious that my improvement may 95 be applied to many different styles or makes of lanterns, with but few slight modifications or changes, without departing from the spirit of my invention.

Having thus described my invention, what 100 I claim as new and desire to secure by Letters Patent, is—

1. In a lantern, the combination with the guard-ring, the oil-pot, and the burner, of a wick-raising mechanism comprising a bell-shaped part journaled on the burner and telescoping the oil-pot, the top of said part having a circular rack concentric to the burner, the bottom of said part having an annular flange facing the guard ring, the 110 said flange comprising a second circular rack, a wick-raising spindle having a pinion engaging the first rack, and a shaft journaled in one side of the guard ring and supporting a pinion engaging the second rack. 115

2. The combination with the oil-pot, of a bell-shaped gear partially telescoping said pot and permanently attached thereto, said gear comprising a plurality of horizontal circular racks, one of said racks cut in the top of said bell, the second rack being cut in a horizontal flange disposed below the first rack, a pinion constantly in mesh with said first rack, and a pinion carried by the guard ring of a lantern adapted to be engaged by 120 said second rack when the oil pot is inserted in the lantern frame.

3. The combination with the movable oil-

pot of a lantern, of a bell gear partially telescoping the top of the oil pot and movable with said pot, said gear journaled for rotary movement independent of said pot, said gear

5 comprising two concentric racks, a pinion constantly engaging the smaller of said racks and movable with said gear and pot, and a

pinion carried by the guard ring of the lantern adapted to engage the larger of said racks while said pot is inserted in the lantern 10 frame.

In testimony whereof I affix my signature.

RICHARD J. KELLY.
